UNITED STATES PATENT OFFICE

150,738

DESIGN FOR A BRACELET

Theodore F. Strub, Chicago, Ill.

Application March 27, 1947, Serial No. 137,952

Term of patent 14 years

(Cl. D45—4)

To all whom it may concern:

Be it known that I, Theodore F. Strub, a citizen of the United States, residing at Chicago, in the county of Cook and State of Illinois, have invented a new, original, and ornamental Design for Bracelets, of which the following is a specification, reference being had to the accompanying drawing, forming part thereof.

In the drawing:

Fig. 1 is a front perspective view of a bracelet, showing my new design.

Fig. 2 is a rear elevational view of the bracelet, and

Fig. 3 is a side elevational view thereof.

I claim:

The ornamental design for a bracelet, as shown.
